1

Latin name of the genus and species: *Fragaria x ananassa*.

Varietal denomination: 'Dr. Duncan' (a.k.a. '108637').

BACKGROUND OF THE INVENTION

The present invention relates to new and distinct strawberry plant designated as 'Dr. Duncan' (a.k.a. '108637').

'Dr. Duncan' (a.k.a. '108637') is the result of a controlled-cross made in Nov. 18, 2010 between a female parent cultivar designated '107801' (a.k.a. 'Akira') and a male parent cultivar designated '1038578' made by the Inventor and was first fruited in Watsonville, Calif. growing fields. Following selection and during testing, the plant was originally designated '108637' and subsequently named 'Dr. Duncan'. 'Dr. Duncan' is a day-neutral plant.

This new strawberry plant was asexually reproduced via runners (stolons) by the inventor at Watsonville, Calif. Asexual propagules from the original source have been tested in Watsonville growing fields and to a limited extent, grower fields in high elevation. The properties of this plant were found to be transmissible by such asexual reproduction. The plant is stable and reproduces true to type in successive generations of asexual reproduction.

BRIEF SUMMARY OF THE INVENTION

This invention relates to new and distinctive strawberry plant designated as 'Dr. Duncan' (a.k.a. '108637'). The plant is primarily adapted to the climate and growing conditions of the central coast of California. This region provides the necessary temperatures required for it to produce a strong vigorous plant and to remain in fruit production from March through October. The nearby Pacific Ocean provides the needed humidity and moderate day temperatures and evening chilling to maintain fruit quality for the production months.

Dr. Duncan (a.k.a.

The present invention provides new and distin-

plant designated as 'Dr. Duncan' (a.k.a. '1086

Drawing Sheets

The present invention provides new and distinct strawberry plant designated as 'Dr. Duncan' (a.k.a. '108637').

8 Drawing Sheets

2

'Dr. Duncan' has not been observed under all possible environmental conditions, and the phenotype may vary significantly with variations in environment, however with no variance in genotype. The following observations, measurements, and comparisons describe this plant as grown under normal conditions in Watsonville, Calif. unless otherwise noted.

The following traits and photographs in combination distinguish strawberry plant 'Dr. Duncan' from known strawberry plants. Plants for the botanical measurements in the present application were grown as annuals. Any colour references are made to The Royal Horticultural Society Colour Chart, 1995 Edition, except where general terms of ordinary dictionary significance are used. The plants were 8-month old when the observation was made.

TABLE 1

'Dr. Duncan' Characteristics		
	Characteristic	Description
20	General	Plant Habit
		Plant Growth Habit
		Day length
		Planting season
		Height
		Width
		Density of foliage
		Plant vigor
		Rain/weather tolerance
		Harvest Ease
25	Leaf	Crown diameter
		Fertility
		Freezing quality
		Leaf Shape
		Leaf blistering
30	Leaf	Leaf glossiness
		Leaf variegation
		Leaflets per leaf
		Number of leaflets
		113
35		

TABLE 1-continued

'Dr. Duncan' Characteristics		
Characteristic	Description	
Terminal leaflet width	72 mm	
Terminal leaflet length	84 mm	
Terminal leaflet length/width ratio	1.17	
Teeth per terminal leaflet	18 to 23	
Shape of terminal leaflet	Orbicular	
Shape of the terminal leaflet base	Acute	
Shape of terminal leaflet in cross-section	Concave	
Shape of the terminal leaflet margin	Serrate	
Color of upper side of leaflet	RHS 137A	
Color of lower side of leaflet	RHS 137C	
Terminal leaflet margin	flat	
Leaf blistering	Weak	
Leaf glossiness	Medium	
Leaf variegation	Absent	
Number of leaflets	113	
Terminal Leaflet margin	Flat	
Terminal Leaflet shape	Orbicular	
Terminal Leaflet shape of base	Acute	
Terminal Leaflet shape of apex	Rounded	
Leaflets per Leaf	3	
Shape of terminal leaflet	Orbicular	
Shape of the terminal leaflet apex	Rounded	
Limbs	Petiole length	21 cm
	Petiole diameter	3.42 mm
	Petiole pubescence	Sparse
	Petiole pose of hairs	Horizontal
	Petiole color	RHS 144A
	Petiole length	1.3 cm
	Petiole diameter	2.56 mm
	Petiole color (color code)	RHS 145B
	Stipule length	3.7 cm
	Stipule width	1.7 cm
Inflorescence	Stipule pubescence	Medium to Dense
	Stipule anthocyanin	Present
	Stipule color (color code)	RHS 145A
	Stipule anthocyanin color (color code)	RHS 184D
	Pedicel color (color code)	RHS 145A
	Pedicel length	10.5 cm
	Pedicel diameter	2.66 mm
	Attitude of hairs on petiole and pedicel	Slightly Outwards to Horizontal
	Peduncle size	Medium to Large
	Peduncle length	25.5 cm
Flower	Peduncle diameter	3.71 mm
	Peduncle color (color code)	RHS 145B
	Peduncle pubescence	medium
	Attitude of hairs on peduncle and pedicel	Slightly outwards to horizontal
	Inflorescence position relative to foliage	Above
	Time of flowering (50% of plants in bloom)	April
	Flower arrangement of petals	Touching
	Flower size	Medium to Large
	Flower diameter	2.5 cm
	Number of Flowers per Truss	3 to 10
Petal	Petal shape	Orbicular
	Petal apex	Rounded
	Petal margin	Entire
	Petal base shape	Concave
	Petal spacing	Touching
	Petal length	1.6 cm
	Petal width	1.5 cm
	Petal length/width ratio	1.07
	Petal number per flower	5 to 7
	Number of flowers	21 to 34
Upper Petal	Upper Petal color	RHS 155C
	Lower Petal color	RHS 155D

TABLE 1-continued

'Dr. Duncan' Characteristics		
Characteristic	Description	
5	Calyx diameter	3.1 to 4.2 cm
	Corolla diameter	2.5 cm
	Calyx diameter relative to corolla	Larger
10	Inner Calyx diameter relative to outer	Equal
	Sepal shape	Elliptical
	Sepal apex	Convex
	Sepal margin	Entire
	Sepal number per flower	9 to 15
	Sepal length	2 to 2.5 cm
	Sepal width	1.0 to 1.1 cm
	Receptacle color	RHS 145B
	Self Fertility	Not Tested
	Time of flowering (50% of plants in bloom)	April
20	Shape of stigma	Capitate
	Color of stigma	RHS 4A
	Length of style	2 mm
	Color of style	RHS 12A
	Color of the ovary	RHS 145A
	Receptacle color	RHS 145B
	Number of stamen	21 to 25
	Length of the stamens	2.0 to 3.5 mm
25	Shape of anther	Dorsifixed
	Size of anther	1.5 to 2.0 mm
	Color of anther	RHS 22A
	Anther diameter	1.2 mm
	Anther length	1.6 mm
	Amount of pollen	Moderate
	Color of pollen	RHS 13B
	Color of filament	RHS 145C
	Length of filament	2.0 to 5.0 mm
30	Stolon number	2 to 3
	Stolon anthocyanin	RHS 183A
	Stolon thickness	Thin to Moderate
	Stolon pubescence	Heavy
	Stolon Length	72 cm
	Widest diameter of stolon at leaf attachment	3.30 mm
	Stolon color	145B
	Fruiting truss length	7.0 to 13.0 cm
	Fruiting truss diameter	3.76 mm
	Number of fruit per truss	1 to 7
	Shape difference between primary & secondary fruits	No difference
40	Fruit calyx diameter	5.9 cm
	Fruiting truss attitude	Horizontal to Slightly Outwards
45	Truss color	RHS 145A
	Fruit length	4.92 cm
	Fruit width	4.22 cm
	Fruit skin color	RHS 145A
	Fruit flesh color excluding core	RHS 44A
50	Fruit core color	RHS 41B
	Fruit length/width ratio	1.17
	Fruit weight	23 g
	Relative fruit size	Medium
	Predominant fruit shape	Globoso Conic
	Shape difference between primary & secondary fruits	No Shape Difference
55	Width of band without of achenes	Medium
	Fruit glossiness	Medium to Strong
	Position of achenes	Even to Below Surface
	Achene color	RHS 145A
60	Achenes per fruit	325
	Achene weight	0.19 g
	Position of calyx	Even
	Level of adherence of calyx	Medium to Strong
	Color of calyx	RHS 136A
	Pose of calyx segments	Spreading to Reflexed
65	Fruit calyx diameter	5.9 cm

TABLE 1-continued

'Dr. Duncan' Characteristics	
Characteristic	Description
Size of calyx in relation to fruit	Equal to Larger
Firmness of flesh	Medium
Color of the flesh	RHS 45A
Evenness of flesh color	Nearly Even
Fruit hollow core length	2.4 cm
Fruit hollow core width	0.8 cm
Fruit hollow length/width ratio	3.00
Hollow center	Medium
Sweetness (Brix)	8
Acidity (pH)	3.78
Texture when tasted	Fine
Time of flowering	April
Time of fruit ripening	May
Harvest maturity (50% of plants with ripe fruit)	May
Type of bearing	Day Neutral
Grams of fruit per plant (June)	907 g
Firmness	Firm
Surface Texture	Smooth
Appearance Score (1 to 5 with 4 = best)	4
Storage longevity	5 to 10 Days
Cull rate: 1- % Usable	10%
Yield per plant per season	2.6 kg

'Albion' (U.S. Plant Pat. No. 16,228) is a commercial strawberry variety that is similar to, but distinguished from 'Dr. Duncan'. The fruit yield of 'Dr. Duncan' exceeds the yield of 'Albion' in multiple annual testing cycles performed at the breeders test location in Watsonville Calif. 'Dr. Duncan' does not produce large quantities of stolon (runners) during the fruiting period after propagation in California nurseries and Watsonville fruiting field, which saves labor of about \$1,500 per acre because stolon must be removed in order to effect efficient harvest and continued

flowering. 'Albion' produces abundant quantities of stolon that must be cut by hand labor in the fruiting field.

The fruit 'Dr. Duncan' is darker in redness coloration than its parent 'Akira'. The foliage of "Akira" is very dark green compared to the medium green coloration of the foliage of 'Dr. Duncan'. The foliage and plant structure of parent 'Akira' was observed to be more dense than the foliage of 'Dr. Duncan'.

The foliage and plant structure of the male parent of 'Dr. Duncan' was observed to be denser than the foliage of 'Dr. Duncan'. 'Dr. Duncan' has a significantly higher yield and a significantly higher percentage of marketable fruit compared to its male parent. The fruit of 'Dr. Duncan' is a much darker red and slightly smaller than the fruit of its female parent.

DESCRIPTION OF THE DRAWINGS

The accompanying color photographs depict various characteristics of the cultivars as nearly true as possible to make color reproductions.

FIG. 1 shows 'Dr. Duncan' plants growing in the field with inflorescences in mid June about 8-month old.

FIG. 2 shows 'Dr. Duncan' plants growing in the field with multiple fruits.

FIG. 3 shows the front side of inflorescences of 'Dr. Duncan' plants.

FIG. 4 shows the back side of inflorescences of 'Dr. Duncan' plants.

FIG. 5 shows the front side of a leaf of 'Dr. Duncan' plants.

FIG. 6 shows the back side of a leaf of 'Dr. Duncan' plants.

FIG. 7 shows fruits of 'Dr. Duncan' plants.

FIG. 8 shows fruits of 'Dr. Duncan' plants cut in half.

The invention claimed is:

1. A new and distinct cultivar of strawberry plant named 'Dr. Duncan', substantially as shown and described herein.
